SEAL

Winfred M. Brooks, West Orange, N. J., assignor
to E. J. Brooks Company, Newark, N. J., a corporation of New Jersey

Application July 23, 1947, Serial No. 763,005

1 Claim. (Cl. 292—322)

1

This invention relates to sealing means and has for its main object and feature the provision of means for attaching a seal to a compressible object of non-uniform size, such as meat, poultry and fish, although it is to be understood that the invention is not limited in its use to commodities of that character.

In the accompanying drawings, the invention is shown embodied in several forms in which:

Figure 1 is a plan view of the blank as it is cut out of the sheet material and before the parts are bent;

Figure 2 is a sectional view that shows the blank of Figure 1 with the parts bent but before closing the seal;

Figure 3 is a view similar to Figure 2 but with the seal in closed position;

Figure 4 shows a modification of the invention and is a view looking in the direction of arrow 4 of Figure 5;

Figure 5 is a sectional view substantially on the plane of line 5—5 of Figure 4 with the parts bent but before closing the seal; and

Figure 6 is a view similar to Figure 5 but with the seal in closed position.

Considering the first form of the invention shown in Figures 1 to 3 inclusive, the seal is of sheet material preferably of sheet metal. The seal is composed of two connected main sections one 10 and the other 11 lying partially bent toward each other and capable of further bending. Two resilient tongues indicated by 12 and 13 are provided, one, 12, at the free end of and inwardly bent over, said first main section 10, and the other tongue, 13, at the free end of the second main section 11, and lying partially bent and pointing toward the tongue of said first main section. Tongue 12 is provided with a slot 14 and, between said slot and the inwardly extending outer end 12a of said tongue, is provided with an inwardly extending resilient retaining member 15, that lies inwardly over and pointing toward said first main section 10. The other tongue 13, which may be in the form of a piercing member to pass through the substance to which the seal is to be attached is provided near its free end with a latching member 16. After the seal has been blanked out as shown in Figure 1, the parts are bent substantially into the position shown in Figure 2, in which position it will be observed that main sections 10 and 11 have been brought partly toward each other and each of the tongues 12 and 13 have been bent inwardly over its complementary main section.

The seal shown in Figure 2 is now ready to be

2

attached to the commodity to be sealed, and meat or the like is placed within the main sections and between the two tongues 12 and 13, after which the parts are bent by pressure of the fingers into the position shown in Figure 3, in which it will be observed that tongue 13 has entered into slot 14, has been deflected by engagement with the walls of the slot and with the interior of its non-complementary main section 10 and is brought into a slidable engagement with retaining member 15, thereby placing the latter under tension or making it into a spring, and said retaining member in turn reacts against tongue 13 and presses the latter into engagement with its non-complementary main section 10, the sliding movement of the parts continuing until latching member 16 has passed the lower end of retaining member 15, and whereby also tongue 12 of the first main section 10 will be deflected by said second main section 11 and both of said tongues 12 and 13 placed under tension. Pressure against the outside of main sections 10 and 11 may now be released and tongue 13 will move backward out of slot 14 until latching member 16 strikes the lower end of retaining member 15, when no further outward movement is possible.

Turning now to the form of the invention shown in Figures 4 to 6 inclusive, it will be seen that the construction is substantially the same as in Figures 1 to 3 inclusive, except that the seal here is intended to seal a cord 17 carrying an identification tag 18. The seal here is composed of two main sections 19 and 20, section 19 being provided with a tongue 21, having a slot 22 and a resilient retaining member 23 that lies bent inwardly over the interior of its complementary main section 19. Main section 20 is provided with a tongue 24, to enter slot 22, having a latching member 25 to engage member 23. In the case of the form shown in Figures 1 to 3 inclusive, it will be noted that main sections 10 and 11 are devoid of side walls, whereas in the form of the invention shown in Figures 4 to 6, side walls 26 and 27 are provided slightly cut away at the point, 28, of bending the two main sections so as to pinch cord 17 in the manner indicated. The closed seal thus produced, as shown in Figure 6, has a completely enclosed structure, whereas the seal shown in Figure 3 has no side walls so as to allow bulky compressible material to extend in between main sections 10 and 11, as will be understood.

I claim:

In a sheet-material seal composed of two connected main sections lying partially bent toward

each other and capable of further bending, the combination with the first of said main sections of a resilient tongue at the free end thereof lying reversely bent over said first main section, said tongue having a slot and, intermediate said slot and the inwardly extending outer end of said tongue, having a resilient retaining member that lies inwardly over and pointing toward said first main section; and a second resilient tongue at the free end of the second of said main sections lying partially bent and pointing toward the tongue of said first main section and said second tongue having, near its free end, a latch member, whereby when the main sections are pressed together the tongue on said second main section will enter the slot of said first main section and will be depressed by engagement with said first main section and will pass between the

latter and the retaining member thereby placing said retaining member under tension and bringing said latch member past the inwardly extending outer end of said retaining member, and whereby the tongue of said first main section will be deflected by the second main section, and both of said tongues placed under tension.

WINFRED M. BROOKS.
